AIR CONDITIONING SYSTEM

Ralph H. Metcalf, Webster Groves, Mo., assignor
to Minneapolis-Honeywell Regulator Company,
Minneapolis, Minn., a corporation of Delaware

Application March 18, 1938, Serial No. 196,682

11 Claims.

(Cl. 257—3)

This invention relates to air conditioning and is more particularly concerned with automatic controls for providing efficient and economical operation of systems of this character.

5 It is an object of my invention to provide a relatively simple automatic control system for an air conditioning installation, which is adapted to operate the various air conditioning instrumentalities in a manner for maintaining proper operating conditions in summer, in winter, and during in-between seasons. More specifically, it is an object of my invention to provide an air conditioning control system which provides for three distinct operating sequences for the air conditioning apparatus, one for summer, one for in-between seasons, and one for winter.

10 It is a further object of my invention to provide an air conditioning control system for air conditioning apparatus which is especially adapted to handle applications in which the dehumidifying load is quite heavy as compared to the sensible heat or cooling load. More specifically, it is an object of my invention to provide an air conditioning control system which utilizes fresh air for dehumidifying the space so long as the condition of the fresh air is suitable for this purpose and which uses no more fresh air than is necessary for this purpose to thereby reduce the cost of heating this air to a minimum.

15 20 It is a further object to provide a control system for an air conditioning system of the type just described having artificial dehumidifying means, the control system functioning to place this dehumidifying means into operation only when the dehumidifying action of the fresh air is insufficient for maintaining proper humidity within the conditioned space.

25 30 Still another object of my invention is the provision of a control system which utilizes the dehumidifying effect of fresh air so long as the condition of the fresh air is suitable for this purpose, but which automatically restricts the flow of fresh air to the space when the fresh air condition becomes unsuitable for this purpose, and which provides for increasing the dehumidifying action of an artificial dehumidifying means when the flow of fresh air is so restricted.

35 40 Still another object of my invention is the provision of a system which automatically controls the flow of fresh air into a space in accordance with relative humidity, but which restricts the flow of air to the space irrespective of relative humidity within the space whenever the outdoor temperature falls below a predetermined value.

45 50 55 Further objects consist in the provision of

various combinations and sub-combinations of control apparatus, and will become apparent from the following description and the appended claims.

For a full disclosure of my invention, reference is made to the following detailed description and the accompanying drawing, the single figure of which indicates diagrammatically an air conditioning control system embodying one form of my invention.

Referring to the drawing, reference character 1 indicates an air conditioning chamber having a return air inlet duct 2 which may lead from a space being conditioned, and a fresh air inlet duct 3. The discharge end of the conditioning chamber 1 is connected to a fan 4 which discharges air through a discharge duct 5 to the space being conditioned. Located within the conditioning chamber 1 is a direct expansion type cooling and dehumidifying coil 6. This cooling coil in turn is connected to a pair of compressors 7 and 8 which discharge through a conduit 9 into a condenser-receiver 10. The outlet of this condenser-receiver is connected by a liquid line 11 to an expansion valve 12 located at the inlet of the coil 6. This expansion valve may be of any desired type, and if desired may be of the thermostatic type illustrated, having a bulb 13 attached to the discharge conduit 14 of the cooling coil 6. This discharge conduit in turn is connected to the inlets of the compressors 7 and 8. The system just described therefore forms a conventional refrigeration system wherein operation of the compressors 7 and 8 cause chilling of the cooling coil 6 in a manner well understood in the art.

The cooling coil 6 is shown as extending but part-way across the conditioning chamber 1 for providing a by-pass 15 for the air around the cooling coil. The flow of air through this by-pass 15 is controlled by means of a by-pass damper shown as consisting of a set of dampers 16 which are actuated through a suitable linkage by means of a proportioning motor 17. This proportioning motor may be of any suitable type and is preferably of the type shown in Patent 2,028,110 issued to Daniel G. Taylor on January 14, 1936. This proportioning motor is controlled by means of a space relative humidity controller as will be described hereinafter.

In order to increase the dehumidifying effect of the coil 6 there is provided a pre-cooling and reheating circuit utilizing a heat exchanger 18 which is located in the conditioning chamber on the upstream side of the cooling coil 6 and a second heat exchanger 19 which is located on the

- downstream side of this cooling coil. The upper ends of the heat exchangers 18 and 19 are connected together by means of a conduit 20 while the lower ends of these heat exchangers are connected together by a conduit 21, a circulating pump 22 being interposed in this conduit. This pump 22 may be of any suitable form and may be driven by an electric motor 23. Due to the circulation of a heat exchange medium between 10 the heat exchangers 18 and 19, by pump 22, the heat exchanger 18 will absorb heat from the air passing to the cooling coil 6 and this heat will be delivered up by heat exchanger 19 to the cooled air being discharged from the cooling coil 6.
- 15 Due to the pre-cooling action of the heat exchanger 18 the temperature of the air passing to the cooling coil 6 will be reduced to a point nearer its dewpoint than would occur if this pre-cooling action had not taken place. Due to this reduction in temperature of the air, the cooling coil 6 will have less sensible heat to remove from the air before condensation of the moisture in the air begins to take place. The pre-cooling action of the heat exchanger 18 therefore increases the dehumidifying effect of the cooling coil 6. In other words, when the circulating pump 22 is in operation, the cooling coil 6 will be caused to perform a larger proportion of dehumidification than will occur when the pump 22 is out of operation.
- Referring now to the fresh air inlet duct 3, this duct is provided with a preheating coil 25. This coil extends but part-way across the inlet duct to provide a by-pass 26. The flow of heating medium to the preheating coil 25 is controlled by means of a valve 28 which may be actuated by means of a motor 29. This motor may be of any suitable two-position type and is herein shown as being of the type utilizing a three-wire control circuit. The control of this motor will be described later in this specification. The flow of air across the preheating coil 25 may be controlled by means of suitable manual dampers 30 for providing a predetermined minimum supply of fresh air to the space at all times. The flow of fresh air through the by-pass 26, however, is controlled by a fresh air damper consisting of a set of dampers 31 which are actuated through a suitable linkage by means of a proportioning motor 32. This proportioning motor may be of the type disclosed in the Taylor patent mentioned hereinbefore. This proportioning motor 32 is controlled by means of a space relative humidity controller as will be described later.
- 55 Referring to the return air duct 2, this duct may be provided with a set of return air dampers 33 which may be actuated by means of a proportioning motor 34. This proportioning motor is controlled by means of what is termed a dual switch 35 which is actuated by the fresh air damper motor 32. This dual switch 35 consists of a potentiometer which is adjusted by the proportioning motor 32. For purposes of illustration, this potentiometer is shown as comprising a slider 36 which is actuated by the shaft of the motor 32, this slider cooperating with a resistance 37. The potentiometer or dual switch is connected to the damper motor 34 in the usual manner. As shown, the controls are arranged in 60 a manner to cause the recirculated air damper to be closed whenever the fresh air damper 31 is wide open. As the damper 31 is moved towards closed position, the slider 36 will travel downwardly across resistance 37 which will cause 75 the motor 34 to open the damper 33 a propor-

tionate amount. In this manner the dampers 31 and 33 are controlled to operate in unison but in opposite directions so as to control the relative proportions of fresh and return air being supplied to the conditioning chamber 1.

In accordance with my invention, the compressors, the pump 22, the valve 28 and the fresh and return air dampers are controlled in part in accordance with outdoor temperature in a manner to provide one type of operation during the heating season, another type of operation during the cooling season, and still another type of operation during in-between seasons. This control arrangement will now be described. Reference character 38 indicates generally a thermostat including a bellows 39 which is attached by a capillary tube 40 to a control bulb 41 located in the fresh air duct 2. The bulb, tube and bellows contain a suitable volatile fill for causing the pressure within the bellows 39 to vary in accordance with changes in temperature at the bulb 41. The bellows 39 in turn actuates a pivoted mercury switch carrier carrying a mercury switch 42, a spring 43 being provided for biasing the switch 42 towards open position. As the outdoor temperature increases, the pressure within the bellows 39 will increase for tilting the mercury switch 42 towards closed position, against the action of spring 43. This instrument may be so designed and adjusted that when the outdoor temperature is below 35° F. the bellows 39 will be collapsed sufficiently to allow switch 42 to be opened. When the outdoor temperature is above this value, however, the mercury switch 42 will be tilted to closed position as shown.

The mercury switch 42 is connected to control a pair of relays generally indicated as 44 and 45. The relay 44 may include a relay coil 46 which actuates through a suitable armature (not shown) a pair of switch arms 47 and 48. The switch arms 47 and 48 in turn cooperate with "in" contacts 49 and 50 respectively, and with "out" contacts 51 and 52 respectively. When the relay coil 46 is energized the switch arms 47 and 48 will be brought into engagement with the "in" contacts 49 and 50 while when the coil 46 is de-energized, the switch arms 47 and 48 will be caused to engage the "out" contacts 51 and 52 under the action of gravity or springs (not shown). The relay 45 may be identical with the relay 44 and includes a relay coil 53 and a pair of switch arms 54 and 55 which cooperate with "in" contacts 56 and 57 and with "out" contacts 58 and 59.

The energization of the relay coils 46 and 53 is controlled by the mercury switch 42 of the thermostat 38. Thus when mercury switch 42 is closed, the relay coil 46 will be energized as follows: line wire 60, wire 61, mercury switch 42, wire 62, relay coil 46, wire 63 and wire 64 to line 60 wire 65. Inasmuch as the relay coil 45 is connected in parallel with the coil 44 as shown, it will be apparent that when the mercury switch 42 is closed, relay coils 46 and 53 will be energized, while when the mercury switch 42 is open these relay coils will be deenergized.

Reference character 70 indicates generally an outdoor wet bulb temperature responsive thermostat. This thermostat includes a bellows 71 which is connected by a capillary tube 72 to a control bulb 73 in the fresh air duct 2. This control bulb may be provided with a porous cover 74 which may be kept moist in any suitable manner to thereby cause the temperature of the bulb 73 to assume the wet bulb temperature of the 75

fresh air. The bellows 71 may be arranged to control a mercury switch 75. This instrument may be so designed and adjusted as to cause the mercury switch 75 to be closed whenever the wet bulb temperature of the fresh air is above a predetermined value such, for instance, as 55° F., while causing the switch to be open as shown when the wet bulb temperature of the fresh air is below this value. The mercury switch 75 is arranged to control the relay coil 76 of a relay generally indicated as 77. This relay may be of the same general construction as the relays 44 and 45 and includes a pair of switch arms 78 and 79. The switch arm 78 cooperates with contacts 80 and 81, while the switch arm 79 cooperates with a contact 82. When the mercury switch 75 is closed, the relay coil 76 will be energized as follows: line wire 60, wire 83, mercury switch 75, wire 84, relay coil 76, wire 85 and wire 64 to line wire 65. It will therefore be seen that when the wet bulb temperature of the fresh air is below 55° F., the relay coil 76 will be deenergized as shown, while when the wet bulb temperature rises above this value the relay coil 76 will be energized. The functions of the relays 44, 45 and 77 will become apparent as this description proceeds.

Referring now to the control of the compressors 7 and 8, these compressors are provided with magnetic starters 88 and 89 respectively. These magnetic starters may be of any desired type. The starter 88, for illustration, may comprise a starter coil 90 which actuates switch arms 91, 92 and 93 which are adapted to connect and disconnect the compressor motor 94 to or from the three-phase line wires 94a. It will be understood that when the coil 90 is energized, the compressor 7 will be placed into operation, while when the coil 95 of starter 89 is energized, the compressor 8 will be placed into operation.

40 Energization of the coils 90 and 95 may be controlled by means of a step controller 96. This step controller may comprise a proportioning motor 97 which may be of the type shown and described in the Taylor patent. This motor 97 is provided with an operating shaft 98 carrying cams 99 and 100 which actuate mercury switches 101 and 102 respectively. The cams 99 and 100 are arranged in staggered relationship on the shaft 98 as shown. With the arrangement illustrated, as the shaft 98 is rotated in a clockwise direction the mercury switch 102 will be tilted to closed position. This will energize the starter coil 90 as follows for placing the compressor 7 into operation: line wire 104, wire 105, mercury switch 102, wire 106, starter coil 90 and wire 107 to line wire 108. Upon further rotation of the shaft 98 in this same direction, the mercury switch 101 will be tilted to closed position which will energize the starter coil 95 for placing the compressor 8 into operation. It will therefore be apparent that when the shaft 98 of the step controller is at its extreme counter-clockwise limit of rotation, the mercury switches 101 and 102 will be open and consequently both compressors will be out of operation. As the shaft 98 rotates in a clockwise direction, however, first the compressor 7 will be placed into operation and upon further rotation of the shaft 98 the compressor 8 will be placed into operation.

70 The proportioning motor 97 of the step controller 96 may be controlled in accordance with the load on the system by means of a thermostat 110. This thermostat may comprise a bellows 111 which is connected by a capillary tube 112 to a control bulb 113 which is attached to the cooling

coil 6. The bulb, tube and bellows contain a suitable volatile fluid for causing the pressure in the bellows 111 to vary with changes in temperature at the cooling coil 6. The bellows 111 may actuate a bell crank lever having an actuating arm 5 114 and a control arm 115 which cooperates with a control resistance 116 to form a control potentiometer. When the cooling coil temperature is low the bellows 111 will be contracted by means of a spring 117 for causing the control arm 115 to 10 engage the left-hand end of resistance 116 as shown. As the temperature of the cooling coil 6 increases, however, the pressure within bellows 111 will increase for causing movement of the control arm 115 to the right across the resistance 15 116.

The motor 97 is provided with a three-wire control circuit including a common control wire 118 and a pair of control wires 119 and 120. Upon reference to the Taylor patent, it will be noted 20 that the motor 97 is adapted to assume positions depending upon the relative amounts of resistance connected between the common control wire 118 and the wire 119 and between the wire 118 25 and the wire 120. This adapts the motor 97 for control by a potentiometer such as 115-116 of the thermostat 110. Referring to the wiring between the motor 97 and the thermostat 110, it will be noted that the common control wire 118 is 30 connected to the switch arm 48 of the relay 44. The "in" contact 50 in turn is connected by a wire 121 to the control arm or slider 115 of thermostat 110. Thus when the outdoor dry bulb temperature is above 35° the relay coil 46 is energized 35 and this causes the common control wire of motor 97 to be connected to the slider 115 of thermostat 110. The control wire 119 of the motor 97, it will be noted, is connected to the right-hand end of resistance 116, while the control wire 120 is connected through wire 122 to the left-hand end 40 of resistance 116.

With the slider 115 engaging the left-hand end of resistance 116, the common control wire 118 is connected directly to the control wire 120 as follows: wire 118, switch arm 48, contact 50, wire 45 121, slider 115, wire 122 to wire 120. At this same time the entire resistance 116 is interposed between the wire 118 and the wire 119. This causes the proportioning motor 97 to assume the extreme counter-clockwise position shown, in 50 which the mercury switches 101 and 102 are open, thereby causing the compressors 7 and 8 to be out of operation. As the cooling coil temperature increases, however, the slider 115 will traverse the resistance 116 which will interpose part of the 55 resistance 116 between the control wires 118 and 119 while decreasing the portion of this resistance between the control wires 118 and 120. This action will cause the proportioning motor to rotate in a clockwise direction an amount proportionate to the movement of the slider 115 on resistance 116. It will thus be seen that as the temperature of the cooling coil 6 increases, the proportioning motor 97 will be caused to rotate, this first placing the compressor 7 into operation. As 65 the cooling coil temperature continues to increase, the motor 97 will be rotated further for placing the compressor 8 into operation.

The arrangement just described acts to control the compressors 7 and 8 in accordance with the 70 load upon the cooling coil. Thus as the load on the coil increases, its temperature will increase and this action will first place one compressor into operation and if the load increases sufficiently the other compressor will be placed into opera- 75

ation. While I utilize a thermostat responsive to cooling coil temperature for controlling the compressors 7 and 8, other types of control may be utilized. For instance, if desired a suction pressure controller or other suitable type of control may be substituted in place of the thermostat 110. Also, while the bulb 113 is shown as attached to the coil 6, it will be understood that this bulb may be attached to the suction line 14, 10 if so desired.

The control action of the thermostat 110 as above described will occur only when the switch arm 48 of the relay 44 is engaging the contact 50. When the dry bulb temperature of the fresh air falls below 35° F., the relay coil 44 will be deenergized as previously described, this causing the switch arm 48 to disengage contact 50 and to engage the contact 52. This will disconnect the slider 115 of the thermostat 110 from 15 the control wire 118 and will directly connect the control wire 118 to the control wire 120, which will have the action of causing motor 97 to rotate to its extreme counter-clockwise limit of rotation in which the compressors 7 and 8 are placed out 20 of operation. It will therefore be seen that when the outdoor dry bulb temperature is above 35° F., the compressors will be controlled in accordance with the load upon the cooling coil 6 while when the outdoor temperature is below 35° F., 25 the compressors will be prevented from operating.

As mentioned hereinbefore, the fresh air damper 31 and the by-pass damper 16 are controlled in accordance with the relative humidity within the space. This control may be effected by means 30 of a space relative humidity controller 130. This controller may include a humidity responsive device 131 comprising a plurality of strands of hair or other moisture responsive material, this device being secured at one end to a fixed support as 35 shown, while being secured at its other end to an actuating arm 132 of a bell crank lever including a control arm or slider 133. The slider 133 is arranged to cooperate with a control resistance 134 and a contact strip 135 for forming 40 a control potentiometer. As the space relative humidity decreases, the strands 131 will shrink against the action of a spring 136 for causing the slider 135 to rotate in a clockwise direction. Upon an increase in relative humidity the strands 45 will expand for permitting opposite movement of the slider 133 under the action of the spring 136. The humidity responsive device 131 may also be arranged to actuate a second control potentiometer consisting of a slider 137 which 50 operates with a resistance 138 and a contact strip 139. The slider 137 may be actuated in any suitable manner such as by an insulated link 140 connected to the slider 133.

The control potentiometer formed of slider 133, 55 resistance 134 and contact strip 135, is arranged to control the by-pass damper motor 17. Referring to the wiring, it will be noted that the contact strip 135 is connected directly to one terminal of the motor 17 by a wire 141, while the resistance 134 is connected to another terminal of the motor 17 by a wire 142. The slider 133, however, is connected by a wire 143 to the "in" contact 57 of the relay 45. The switch arm 55 of this relay is connected to the common control 60 terminal of motor 17 by means of a wire 144. Thus when the outdoor temperature is above 35° F. the switch arm 55 will engage the contact 57 for placing the humidity controller 130 in control of the by-pass damper motor 17. When the outdoor temperature falls below this value, however, 65

the relay coil 53 will be deenergized as previously described to cause the switch arm 55 to engage the contact 59. This will disconnect the slider 133 of the humidity controller from the motor 17 while directly connecting the common control 5 wire 144 of the motor 17 to the control wire 142 through a circuit including contact 59 and wire 142a. This will have the result of causing the motor 17 to run to a position in which the bypass damper 16 is completely closed. 10

The humidity controller potentiometer formed of slider 137, resistance 138 and contact strip 139 controls the fresh air damper motor 32. Referring to the wiring between this potentiometer and the motor 32, it will be noted that the slider 137 is connected by means of a wire 150 to the contact 56 of the relay 45. The switch arm 54 of this relay is connected by a wire 151 to contact 81 of relay 77. The cooperating switch arm 78 in turn is connected by a wire 152 to the common control terminal of the proportioning motor 32. In addition, the resistance 138 is connected to one control terminal of motor 32 by wire 153, and the contact strip 139 is connected to the other motor control terminal by wire 154. By 20 the wiring arrangement just described, it will be apparent that when the relay coil 45 is energized and the relay coil 77 is deenergized, the slider 137 will be connected to the common control terminal of motor 32 as follows: slider 137, wire 150, 30 contact 56, switch arm 54, wire 151, contact 81, switch arm 78 and wire 152 to the common motor control terminal. Therefore, when the outside temperature is between the limits of 35° F. dry bulb and 55° F. wet bulb, the relays 45 and 35 77 will be in the positions shown for placing the humidity controller 130 in control of the fresh air damper motor. However, if the outside dry bulb temperature falls below 35° F., the relay coil 53 of relay 45 will be deenergized thus causing the switch arm 54 to disengage contact 56 and engage contact 58. This will disconnect the slider 137 from the common control terminal of motor 32. Engagement of the switch arm 54 with contact 58 will also directly connect the common control wire 152 of motor 32 to the control wire 153 as follows: control wire 152, switch arm 78, contact 81, wire 151, switch arm 54, contact 58 and wire 156 to wire 153. This short-circuiting of control wires 152 and 153 will cause the motor 32 to run to a position for completely closing the fresh air damper 31. Also, if the outdoor wet bulb temperature rises above 55° F., the relay coil 16 of relay 77 will be energized thereby causing the switch arm 78 to engage the contact 80. This again will disconnect the slider 137 of the humidity controller from the motor 32. Also, the engagement of switch arm 78 with the contact 80 will connect the common control wire 152 of motor 32 to the control wire 153, which will cause the motor to run to a position in which the fresh air damper is completely closed.

From the foregoing description of the fresh air damper control, it should be apparent that when the outdoor temperature is between the limits of 35° F. dry bulb and 55° F. wet bulb, the humidity controller 130 will be placed in control of the fresh air damper. However, if the outside temperature falls below 35° F. dry bulb or rises above 55° F. wet bulb, the fresh air damper 70 will be completely closed irrespective of the value of space relative humidity.

Referring again to the humidity controller 130, it will be noted that the sliders 133 and 137 operate sequentially upon their respective con-

tro resistances 134 and 138. In other words, when the slider 137 engages resistance 138 the slider 133 will ride upon contact 135, while when the slider 133 engages resistance 134 the slider 137 will engage contact 139. The purpose of this arrangement is to provide sequential control of the fresh air damper 31 and the by-pass damper 16. The advantages of this type of control of the dampers 16 and 31 will be explained more fully under "operation."

In order to provide for heating the space during the heating cycle and for providing the necessary reheat for obtaining dehumidification during the cooling cycle, a pair of reheaters 160 and 161 may be provided. The flow of heating medium to the reheater 160 may be controlled by means of a valve 162 which is actuated by means of a proportioning motor 163. This proportioning motor in turn may be controlled by means of a return air thermostat 164 which includes a bellows 165 connected by a capillary tube 166 to a control bulb 167 in the return air duct 2. The bellows 165 actuates an actuating arm 168 of a bell crank lever including a control arm 169. The control arm 169 cooperates with a control resistance 170 and a contact strip 171 to form a control potentiometer for controlling the valve motor 163. As the space temperature decreases, the pressure within bellows 165 will decrease for causing control arm 169 to be shifted to the right across control resistance 170 which in turn will cause the proportioning motor 163 to open the valve 162 for placing the reheater 160 in operation.

The flow of heating medium to the reheater 161 may be controlled by a valve 172 under the control of a proportioning motor 173. This proportioning motor may be controlled by means of a control potentiometer including a slider 174, a resistance 175 and a contact strip 176. With the arrangement shown, it will be apparent that the valves 162 and 172 will be controlled in sequence. For example, when the space temperature is high the bellows 166 will be expanded for causing the sliders 169 and 174 to engage the right-hand ends of contact 171 and resistance 175 respectively. This would cause valves 162 and 172 to be closed. As the space temperature begins to fall, the slider 174 will move across resistance 175 for causing the valve 172 to be opened. At this time, the valve 162 will be kept closed due to the fact that slider 169 is traversing contact 171. However, if the space temperature falls low enough to cause the slider 169 to engage resistance 170, the valve 162 will be opened. The arrangement just described, therefore, provides for sequential control of the reheater valves 162 and 172 in accordance with variations in space temperature.

60

Operation

With the parts in the position shown, the outdoor temperature is above 35° F. dry bulb as indicated by the mercury switch 42 being closed. This has caused the relay coils 46 and 53 to be energized. The resulting engagement of the switch arm 47 with the contact 59 of relay 44 connects the common control wire 180 of the preheater valve motor 111 to the wire 181, which causes the motor 29 to assume a position in which the valve 28 is closed. The preheater 25 is therefore out of operation. Also, due to the switch arm 48 engaging the contact 50 the thermostat 110 is placed in control of the step controller 96. The compressors 7 and

8 are therefore under the control of the load indicating thermostat 110. At this time also, the switch arm 55 of relay 45 is engaging the contact 57 which places the by-pass damper motor 17 under the control of the humidity controller 130. At this time the outside air temperature is below 55° F. wet bulb as indicated by the mercury switch 17 being opened. This causes the relay coil 76 of relay 77 to be deenergized, thus causing switch arm 78 to engage contact 81. Due to the switch arm 54 of relay 45 engaging the contact 56, the fresh air damper motor 32 is placed under the control of the humidity controller 130. Due to the switch arm 79 being disengaged from the contact 82, the starter coil 182 for pump motor 23 is deenergized which causes the motor 23 of circulating pump 22 to be deenergized. The pre-cooler 18 and reheater 19 are therefore not in operation. Also at this time, the space relative humidity is at an intermediate value as indicated by the humidity controller assuming an intermediate position in which the sliders 133 and 137 engage the junctions between their respective resistances and contact strips. Due to the slider 133 engaging the right-hand end of resistance 134, the damper motor 17 has assumed a position in which the by-pass damper 16 is wide open. Also due to the slider 137 engaging the left-hand end of resistance 138, the fresh air damper motor 32 has completely opened the fresh air damper 31. Due to the outdoor temperature being fairly cool a heating load has been placed on the system, this causing the return air controller 164 to assume an intermediate position in which the valve 172 for the reheater 161 is open. At this time, however, the valve 162 for reheater 160 is closed.

When the outside air temperature is between the limits 35° F. dry bulb and 55° F. wet bulb, it is suitable for dehumidifying the space. At this time, it will be noted that due to the space relative humidity being at an intermediate value, the fresh air damper 31 is wide open for utilizing a maximum amount of fresh air for preventing further rise in humidity within the space. If this fails to prevent the space relative humidity from increasing due, for instance, to the fresh air temperature being of higher humidity than usual, or due to a heavy dehumidifying load, the space relative humidity will continue to increase. This will cause the slider 133 to traverse the resistance 134 thereby causing the by-pass dampers 16 to be closed an amount proportionate to the rise in humidity. This will cause air to flow through the cooling coil 6 which will cause dehumidification of the air being passed to the space, this tending to prevent further rise in relative humidity. It will be apparent that as the relative humidity increases above this value the damper 16 will be closed more and more to increase the amount of dehumidification performed on the air supplied to the space. Conversely, as the relative humidity begins falling, the dampers 16 will be opened for decreasing the amount of air passed through the cooling coil. Upon continued fall of the space relative humidity the by-pass dampers will become wide open and upon still further fall in humidity the fresh air dampers 31 will begin to be closed for preventing the relative humidity from falling too low within the space.

It will therefore be seen that one feature of my invention is the provision of a sequential con-

75

trol arrangement for the fresh air damper and the cooling and dehumidifying means. This arrangement, it will be noted, utilizes the dehumidifying action of fresh air for controlling the space 5 relative humidity, and only places the artificial dehumidifying means into operation when the fresh air is no longer capable of preventing the space relative humidity from becoming excessive. It will also be apparent that the control apparatus 10 utilizes no more fresh air than necessary for maintaining the proper humidity within the space, thereby conserving on the heat which must be supplied to the air by the reheaters 160 and 161 under the control of the thermostat 164. This thermostat 164, it will be noted, is always 15 operative to prevent the space temperature from falling below the setting of this thermostat. The heaters 160 and 161 therefore provide for reheat during the cooling season and intermediate season and also provide for heating the space during the heating season.

If the outside temperature should fall below 35° F. it will be quite low in relative humidity when heated to the space temperature and the 20 space relative humidity will not become excessive even though only a small amount of fresh air is supplied. Also, when the outside air falls to this value, considerable heat would be required for heating it to space temperature. It is therefore 25 desirable to completely close the fresh air damper 31 at this time. Thus when the outside temperature falls below 35° F. the thermostat 38 will deenergize the relays 44 and 45. The resulting engagement of the switch arm 54 with the contact 58 will cause the fresh air damper 31 to become completely closed in the manner previously described. Also, the resulting engagement of switch arm 55 of relay 45 with the contact 59 will cause the by-pass damper 16 to become closed. In addition, engagement of the switch arm 48 of the relay 44 with the contact 52 will cause the step controller motor 97 to run to its extreme counterclockwise limit of rotation for preventing operation of the compressors 7 and 8. Furthermore, the engagement of the switch arm 47 of relay 54 with the contact 51 will cause the preheater valve motor 29 to open the valve 28 for placing the preheater 25 into operation. It will therefore be seen that when the outdoor temperature is below 35° dry bulb, the fresh air damper is closed, the preheater 25 is placed into operation, the compressors 7 and 8 are prevented from operating, and the by-pass damper 16 is closed. At this time the return air thermostat 55 30 will control the heaters 160 and 161 in a manner to maintain the desired space temperature.

On the other hand, if the outdoor temperature rises above 55° wet bulb, it will be of little value for maintaining proper humidity within 35 the space. At this time the thermostat 38 will have the relays 44 and 45 energized, which will in the manner previously described cause the preheater valve 28 to be closed and cause the compressor step controller 96 to be placed under the control of the thermostat 110. Also at this time the by-pass damper 16 is under the control of the space relative humidity controller 130. Also, when the outside wet bulb temperature is above 55° F. the relay coil 76 of the relay 77 will be energized. The resulting engagement of the switch arm 78 with the contact 80 will cause the fresh air damper 31 to become completely closed. Also, the engagement of the switch arm 79 with the contact 82 will energize the starter coil 182 of the starter for the pump motor 23. This will

place the pump 22 into operation for causing the precooler 18 and reheater 19 to operate for increasing the dehumidifying action of the cooling coil 6. Therefore, as the outdoor air wet bulb temperature rises to a value indicating that the outdoor air is unsuitable for dehumidifying, the fresh air damper will be closed for preventing entry of fresh air into the space at this time. Due to the loss of this fresh air at low humidity for dehumidifying the space, the cooling coil 6 must provide for a greater amount of dehumidification. It will be noted with the present arrangement that at the time that the fresh air becomes unsuitable for dehumidifying the space, the precooler 18 and reheater 19 are placed into operation for increasing the dehumidifying action of the coil 6 for thereby compensating for the loss of fresh air as a dehumidifying medium. At this time, the space relative humidity will continue to be controlled by the humidity controller 130 which will gradually position the by-pass damper 16 in a manner to increase the air flow through the coil 6 as the space relative humidity increases and for decreasing the air flow through coil 6 as the space relative humidity decreases.

From the foregoing it will be apparent that I have provided an air conditioning control system for an application in which the dehumidifying load is heavy, this system acting to conserve on operating expenses by utilizing fresh air for dehumidifying the space so long as the fresh air is suitable for this purpose. Also with my improved control system, no more fresh air is taken into the space than is necessary in order to maintain the space at proper humidity, and in addition the artificial dehumidification apparatus is not placed into operation unless the dehumidifying effect of the fresh air is insufficient for maintaining proper humidity within the space. In addition, it should be noted that my improved control system acts to restrict the flow of fresh air to the space whenever the fresh air becomes unsuitable for dehumidifying, and also at this time replaces or compensates for the loss of fresh air as a dehumidifying medium by placing the precooler 18 and reheater 19 into operation for increasing the dehumidifying action of the cooling coil 6. Furthermore, it should be apparent that my control system operates to restrict the supply of fresh air to the space when the outdoor temperature falls to a value indicating that only a small quantity of fresh air is necessary for preventing the space relative humidity from becoming excessive. At this time, the fresh air damper is not only completely closed but also the preheater is placed into operation for preventing possible injury to the air conditioning apparatus due to freezing, and in addition the refrigeration means for the system is placed entirely out of operation.

From the foregoing description it will be noted that my control system provides for three distinct cycles of operation of the air conditioning apparatus, one for the heating season, one for the cooling season, and one for intermediate or in-between seasons. Thus during the heating season the fresh air damper is closed and the preheater is in operation while the refrigeration system is out of operation, this action being caused by the thermostat 38. During the intermediate or in-between season the fresh air damper 31 and the by-pass damper 16 are under the control of the humidity controller 130 and the compressors 7 and 8 are under the con- 75

trol of the load indicating thermostat 110, this action being caused by the mercury switch 42 of thermostat 38 being closed simultaneously with the mercury switch 75 of thermostat 10 being opened. During the cooling season the fresh air damper is closed and the precooler and reheater system 19 is in operation, this action being caused by the thermostat 10 energizing the relay 77.

10 While for purposes of illustration I have mentioned specific temperature values at which the controllers may be set, it will be understood that I do not limit myself to these specific values as such values will vary for different installations and applications of my invention. Also, while I have shown and described a preferred form of my invention, it will be apparent that many modifications which are within the scope of my invention will occur to those skilled in the art. I therefore desire to be limited only by the scope of the appended claims and the prior art.

I claim as my invention:

1. In an air conditioning system, in combination, a conditioning chamber for conditioning a stream of air being passed to a space to be conditioned, cooling and dehumidifying means in said chamber, condition responsive means responsive to a condition indicative of the load on the system for controlling the action of said cooling and dehumidifying means, a heat transfer circuit for absorbing heat from the air passing to said cooling and dehumidifying means and for returning the absorbed heat to the air after it has passed through said cooling and dehumidifying means, means for supplying fresh air to said space, flow control means for varying the flow of fresh air, and thermostatic means influenced by a temperature indicative of the type of load on the system for controlling said heat transfer circuit and said flow control means in a manner to place said heat transfer circuit into operation and to decrease the fresh air supply to a minimum when the temperature at said thermostatic means increases to a predetermined value.

2. In an air conditioning system, in combination, a conditioning chamber for conditioning a stream of air being passed to a space to be conditioned, cooling and dehumidifying means in said chamber, a heat transfer circuit for absorbing heat from the air passing to said cooling and dehumidifying means and for returning the absorbed heat to the air after it has passed through said cooling and dehumidifying means, means for supplying fresh air to said space, flow control means for varying the flow of fresh air, means influenced by the moisture content of air conditioned by the system for sequentially controlling said flow varying means and said cooling and dehumidifying means in a manner to increase the supply of fresh air and to increase the action of said cooling and dehumidifying means upon increase in humidity, and thermostatic means influenced by a temperature indicative of the type of load on the system for controlling said heat transfer circuit and for additionally controlling said flow control means, said thermostatic means being arranged to place said heat transfer circuit into operation and to decrease the fresh air supply to a minimum when the temperature at said thermostatic means increases to a predetermined value.

3. In an air conditioning system, in combination, a conditioning chamber for conditioning a

stream of air being passed to a space to be conditioned, condition changing means in said chamber, actuating means for said condition changing means, a by-pass for the air around said condition changing means, by-pass damper means for controlling the relative proportions of the air passed through said condition changing means and through said by-pass, means for supplying fresh air to said space, fresh air damper means for controlling the flow of fresh air, condition responsive means influenced in accordance with the load on the system for controlling said fresh air damper means and said by-pass damper means, and outside temperature influenced thermostatic means for substantially closing both of said damper means when the outside temperature varies to a predetermined value.

4. In an air conditioning system, in combination, a conditioning chamber for conditioning a stream of air being passed to a space to be conditioned, condition changing means in said chamber, actuating means for said condition changing means, a plurality of control devices for said actuating means, motor means for sequentially actuating said control devices, condition responsive means influenced in accordance with the load on the system for controlling the position assumed by said motor means to thereby control the operation of said condition changing means, means for supplying fresh air to said space, flow control means for varying the flow of fresh air, and outside temperature influenced means for controlling said flow control means and for additionally controlling said motor means in a manner to reduce the supply of fresh air to a minimum and to place said condition changing means out of operation when outside temperature varies to a predetermined value.

5. In an air conditioning system, in combination, a conditioning chamber for conditioning a stream of air being passed to a space to be conditioned, condition changing means in said chamber, actuating means for said condition changing means, a plurality of control devices for said actuating means, motor means for sequentially actuating said control devices, condition responsive means responsive to a condition indicative of the load on the system for controlling the position assumed by said motor means to thereby control the operation of said condition changing means, and other condition responsive means influenced by a condition of air passing to said space for additionally controlling said motor means in a manner to cause said motor means to run to a predetermined position when the condition at said second condition responsive means varies to a predetermined value, irrespective of the value of the condition at said first condition responsive means.

6. In an air conditioning system, in combination, a conditioning chamber for conditioning a stream of air being passed to a space to be conditioned, condition changing means in said chamber, actuating means for said condition changing means, a by-pass for the air around said condition changing means, by-pass damper means for controlling the relative proportions of the air passed through said condition changing means and through said by-pass, condition responsive means responsive to a condition indicative of the load on the system for controlling said by-pass damper in accordance with the condition to which said condition responsive means responds, and outside temperature influenced means for additionally controlling said by-pass damper means.

and said actuating means, said outside temperature influenced means being arranged to place said actuating means out of operation and to actuate said by-pass damper means to substantially an extreme position when outside temperature varies to a predetermined value.

7. In an air conditioning system, in combination, means for cooling a space, means for supplying fresh air to said space, flow control means for varying the flow of fresh air, psychrometric condition responsive means for controlling said flow control means and said cooling means, and means including a thermostat influenced by outside dry bulb temperature and a thermostat influenced by outside wet bulb temperature cooperating therewith for additionally controlling said flow control means and said cooling means.

8. In an air conditioning system, in combination, heating means for a space, cooling means for the space, flow control means for varying the supply of fresh air to the space, means responsive to the heat content of the air in the space for controlling said heating and cooling means, changeover relay means for controlling said heating means, said cooling means, and said flow control means, said changeover relay means having three effective positions, a first position in which the flow control means is actuated to restrict the supply of fresh air, and in which the cooling means is prevented from operating, a second position in which the flow control means is actuated to supply a relatively large quantity of fresh air, and a third position in which the flow control means is actuated for reducing the supply of fresh air and in which the heating means is prevented from operating, and outside temperature influenced means for controlling said changeover relay means.

40 9. In an air conditioning system, in combination, heating means for a space, cooling means for the space, flow control means for varying the supply of fresh air to the space, changeover relay means for controlling said heating means, said cooling means, and said flow control means, said changeover relay means having three effective positions, a first position in which the flow

control means is actuated to restrict the supply of fresh air, and in which the cooling means is prevented from operating, a second position in which the flow control means is actuated to supply a relatively large quantity of fresh air, and a third position in which the flow control means is actuated for reducing the supply of fresh air and in which the heating means is prevented from operating, and outside temperature influenced means for controlling said changeover relay means.

10. In an air conditioning system, in combination, air conditioning apparatus for conditioning a space including heating means, cooling means, and fresh air supplying means, means responsive to the condition of the conditioned air for controlling said heating means and cooling means, changeover relay means for controlling said heating means, said cooling means and said fresh air supplying means, said changeover relay means having three effective positions, each of which provides a distinctly different active combination of said air conditioning apparatus, and outside temperature influenced means for controlling said changeover relay means.

11. In an air conditioning system for a space in a building or enclosure, in combination, a conditioning chamber through which air is adapted to be passed for a conditioning action, cooling and dehumidifying means in said chamber, condition responsive means influenced by a condition indicative of the load on the system for controlling the action of said cooling and dehumidifying means, a heat transfer circuit for absorbing heat from the air passing to said cooling and dehumidifying means and for returning the absorbed heat to the air conditioned by said cooling and dehumidifying means, and temperature responsive means influenced by outside temperature for placing said heat transfer circuit out of operation when outside temperature falls to a predetermined value and for placing said cooling and dehumidifying means out of operation when outside temperature falls to a predetermined lower value.

RALPH H. METCALF.
